CALENDAR HOLDER

Henry Finkel, Montreal, Quebec, Canada, assignor to
Bank of Montreal, Montreal, Quebec, Canada

Filed Nov. 4, 1968, Ser. No. 14,309

Claims priority, application Canada Oct. 30, 1968

Term of patent 14 years

Int. Cl. D19—03

U.S. Cl. D74—5

FIG. 1 is a perspective view taken from one end of the calendar holder of my new design;

FIG. 2 is a front view of the calendar holder shown in FIG. 1;

FIG. 3 is an end elevation of the calendar holder shown in FIG. 2;

FIG. 4 is a top plan view of the calendar holder as shown in FIG. 3;

FIG. 5 is a bottom plan view of the calendar holder shown in FIG. 3;

FIG. 6 is a horizontal cross section taken through line 6—6 of FIG. 2.

I claim:

The ornamental design for a calendar holder, as shown.
